UNITED STATES PATENT OFFICE.

CHESTER T. MOREY, OF PROVIDENCE, RHODE ISLAND.

APPARATUS FOR SORTING MACHINE ELEMENTS.

1,424,370.

Specification of Letters Patent. Patented Aug. 1, 1922.

Application filed July 19, 1921. Serial No. 485,993.

To all whom it may concern:

Be it known that I, CHESTER T. MOREY, a citizen of the United States of America, and resident of Providence, in the county of Providence and State of Rhode Island, have invented new and useful Improvements in Apparatus for Sorting Machine Elements, of which the following is a specification.

This invention relates to mechanism for sorting and similarly positioning substantially like elements for subsequent operations thereon and more particularly to means for so sorting and preliminarily positioning machine elements such as to permit of the drilling, tapping or other machining of such elements with accuracy and ease. In the manufacture of nuts, the blanks are punched from material of the proper thickness and usually subjected to several subsequent operations prior to drilling and tapping, whereby the sides are given the desired smoothness of finish and one end is chamfered or rounded to form the top of the finished nut. For the drilling and the tapping of the nut, it is desirable that the tool always enter from a given end of the nut, and in the tapping particularly it is important that the top enter from the top side of the nut in order that the flat or unrounded end of the latter may engage the surface of the work rest, whereby to avoid tipping or tilting of the nut during the operation, and ensuring the perpendicularity of the tapped hole to the bottom face of the nut. It is thus desirable to provide automatic means for similarly arranging the nut blanks for presentation to the drilling and tapping mechanism, and one apparatus suitable for this purpose is disclosed in the patent to Morey, No. 1,841,978, May 25, 1920. While the patented device is eminently suitable for the purpose, the present invention has for its principal object the provision of simple and improved means for performing the desired function. To this end, in lieu of causing the nut to travel to one or another of selected discharge openings in accordance with its initial position and as disclosed in said patent, a movable selector device is employed, providing a plurality of receptacles into either of which the nut may be delivered, the presentation of either of such receptacles in nut receiving position being controlled by the initial position of the nut. Certain of such receptacles may deliver into a common discharge pas-

sage, turning means being provided between such receptacles and passage whereby all nuts received in either of the receptacles will be caused to face in the same direction as they enter the passage.

As the nut blanks delivered to the positioning mechanism are sometimes imperfect by reason of eccentric punching of the openings therein, or through the presence of outstanding fins, etc., it is desirable to provide some means or mechanism whereby the imperfect blanks may be separated or sorted from the perfect blanks, and a further object of the present invention is to provide such sorting means in combination with the positioning mechanism. With this object in view, the movable selector device may be provided with a special receptacle for imperfect blanks, such receptacle opening into an independent passage for the discharge of the rejected blanks.

For properly positioning the selector device, feeler mechanism similar to that disclosed in the aforesaid patent may be provided, but in addition thereto a secondary feeler may also be used whereby to ascertain the presence of imperfectly formed blanks and for determining the position of the selector device for rejecting such blanks.

Fig. 1 is a front elevation of the device, certain parts being in section and other parts, unnecessary to a proper disclosure of the present mechanism, being omitted;

Fig. 2 is a side elevation from the right-hand side of the device as seen in Fig. 1, certain of the parts being broken away;

Fig. 3 is a side elevation of the left-hand side of the machine as viewed in Fig. 1, certain parts being broken away;

Fig. 4 is a plan view of the device with certain parts in horizontal section;

Fig. 5 is a vertical cross section on the line *a—b* of Fig. 4;

Fig. 6 is a vertical cross section on the line *c—d* of Fig. 5;

Fig. 7 is a vertical cross section on the line *e—f* of Fig. 6;

Fig. 8 is a horizontal cross section on lines such as *g—h* of Fig. 5 and *m—n* of Fig. 7;

Fig. 9 is a fragmentary rear elevation of the upper portion of a selector device employed in the mechanism, and also showing pawl devices for controlling the same; and

Figs. 10, 11 and 12 are fragmentary, detail, horizontal cross sections to larger scale

substantially on the line *g*—*h* of Fig. 5 and illustrating the selector device as occupying three different operative positions.

Frame and drive means.

The frame of the machine comprises a base casting 1 from which rise vertical members such as 2, 3. Integral with such vertically extending members is a horizontal table-like device 4. From the upper surface of such table-like device rise brackets 6, 7 supporting a bearing sleeve 8. Within such bearing sleeve is secured a shaft 9 upon which may be mounted a sleeve member 10 having an arm 11 integrally depending therefrom. Such arm forms a portion of the succeeding machine used in the formation of the nuts and is actuated thereby. This arm forms no part of the present invention, and may be omitted from the machine if desired.

Extending outwardly from one of the vertical members of the frame are oppositely directed bosses 12, 13 (Fig. 2) such bosses being provided with a longitudinal bore in which a shaft 14 is mounted for rotation. This shaft projects to the rear of the frame and has secured thereon a cylinder cam 15. The shaft also has mounted loosely thereon a sprocket wheel or other suitable drive element indicated at 16, such sprocket wheel being connected to the shaft as by means of friction discs 17 interposed between the wheel and the cam 15, and by discs 17^a pressed against such wheel by means of a plate 18 serving as an abutment for one end of a spring 19, the opposite end of such spring engaging a collar 20 secured to the shaft by means of a nut 21. By this arrangement the proper driving of the shaft 14 is provided for, while at the same time the possibility of the breakage of the parts, due to jamming of improperly shaped or positioned nuts therein is avoided, as in such case the sprocket wheel 16 is permitted to slip upon the shaft. At its opposite end the shaft 14 is provided with a pair of wiper cams 22, 23, respectively, the purpose of the several cams being described hereinafter.

50

Chute.

Resting upon the upper surface of the frame is a flange 24 (Figs. 4 and 5) such flange being secured to the frame by means of bolts indicated at 25. This flange forms an integral portion of a vertically extending chute 27 which, as indicated in Fig. 4, preferably comprises a casting of channel form, the open side of which may be closed by a removable plate 28, if desired. The longitudinal passage within the casting is of proper dimensions to permit nuts of the desired size to slide down the same edgewise, but is sufficiently restricted to restrain them against any tipping into horizontal position,

While this chute is herein illustrated as a casting, it is contemplated that it might, under some circumstances, be formed otherwise, as for example of sheet metal suitably pressed into the shape, and while the chute has been described as secured in position by means of bolts engaging an integral flange, it is clear that other securing means might well be employed, if desired. This chute may lead from any suitable source of supply such as a rotating feed drum or the like or may be fed directly from a preceding machine or by hand.

Feeler chamber and feeler devices.

The lower end of the chute, at 29, (Figs. 5 and 7) opens into a chamber 30 formed in the upper portion of the frame, this chamber being of substantially rectangular form and having its bottom wall provided with a hardened wear plate 31. This wear plate may be secured to the frame by means of screws 32 or in other desired manner, it being understood that while such wear plate is desirable, it is not essential to the operation of the mechanism. The left hand side wall of the chamber 30 is also provided with a hardened plate, as indicated at 32 (Figs. 5 and 11) such plate being secured in position by means of screws 33. The plate 32 is provided with a centrally arranged, cup-like cavity, (Fig. 11). Extending through the adjacent portion of the frame, and through the plate 32 is a cylindrical bore 35 which opens into the cavity 34 and is concentric therewith. Movable longitudinally of the bore 35 is a plunger member 36, the end of which is provided with a wear plate 37^a secured thereto by means of a screw 38. This wear plate in normal position projects into the cavity 34, as indicated for example in Fig. 11, the outer surface of such wear plate lying substantially in the plane of the outer surface of the plate 32. The plunger 36 is carried by, and as herein illustrated, may be integral with a lever 37, such lever being provided with spaced ears 38, 39 having pivotal engagement with the lower portion of the chute 27. The lever 37 as thus arranged is rockable in a vertical plane, the bore 35 being of a diameter sufficient to permit the plunger 36 to move longitudinally therein while oscillating with the lever 37. The lever 37 projects downwardly below the plunger 36 and is provided with a tail 40.

Mounted in brackets 41 (Fig. 7) projecting from the left-hand side of the frame is a shaft 42, said shaft having secured thereto a bell crank lever provided with an arm 43 having an adjustable stop pin 44 engageable with the tail 40 of the lever 37. The bell crank lever also comprises an arm 45 which extends laterally outward, and which is provided with an opening 46 at its outer end

80

130

125

with which engages the outer end of the coil spring 47, the opposite end of which is secured to an eye-bolt 48 fixed in the upper part of the frame. With the parts as thus arranged the spring 47 tends to rotate the bell crank lever in a clockwise direction, thus carrying the pin 44 into engagement with the tail 40 and thereby normally maintaining the plunger 36 with its inner end projecting into the cavity 34.

The wall of the chamber 30 opposite the plate 32 is formed by the surface 49 of a lever device 50, such lever device being pivoted to oscillate about the axis of a stub shaft 51 (Fig. 5) extending transversely from front to rear of the frame and secured in a suitable opening in one of the vertical frame members, (Fig. 5). This lever device is preferably constructed as indicated in Figs. 5 and 7, comprising parallel web members between which is arranged an anti-friction roll 52 mounted upon a shaft 53 extending through said web members and secured therein. The roll 52 is arranged for engagement with the wiper cam 22 previously described. Interposed between one of the vertical members of the frame and the lever 50 is a compression spring 54, such spring serving normally to maintain the cam roll 52 in engagement with the cam.

A horizontal bore 55 extends through the upper part of the lever 50, opening through the surface 49 into chamber 30 such bore being in substantial axial alignment with the bore 35 previously described. Within the bore 55 is arranged a plunger sleeve 56. A plate 57 is secured to the upper part of the lever as by means of a bolt or screw 58 and serves to cover the right-hand end of the bore 55, as viewed in Fig. 7. Within the sleeve 56 a secondary flange or feeler bar 59 is arranged for longitudinal sliding movement, that end of said bar adjacent to chamber 30 normally being flush with the end of sleeve 56. This bar is provided with a stem 60 which is surrounded by a coil spring 61, such spring being seated within a cylindrical cavity in the sleeve 56 and having one end bearing against an annular shoulder in said cavity. The opposite end of the spring bears against the plate 57. The stem 60 of the feeler bar passes out through an opening in the plate 57 and is provided with a transverse opening through which passes a pivot pin 62 whereby such stem is pivotally secured to a lever arm 63. The lever arm 63 is pivoted at 64 to a bracket 65 carried by the upper part of the lever 50, and at a point below the pivot pin 62 the lever 63 is provided with an adjustable stop pin 66, the inner end of which is engageable with the outer surface of the plate 57. At its lower extremity the lever 63 is provided with an offset contact member 67 and is also provided with an eye-bolt 68 to which one end

of a spring 69 is secured. The opposite end of the spring 69 is fast to a pin 70 secured to the lever member 50 such spring tending normally to move lever 63 and bar 59 to the left. Projecting downwardly from the sleeve 56 is a lug 71 in which is arranged an adjustable stop pin 72 engageable with an adjacent surface of the upper part of lever member 50.

Extending transversely across the frame 75 of the machine, and through suitable bearings therein is a rod 73, the right-hand end of which, as seen in Fig. 8 is arranged for engagement by the contact element 67. At its opposite end the rod 73 is arranged for contact with an arm 74 of a bell crank lever 75, such arm, if desired, being provided with an adjustable contact pin 76 for engagement by the end of such rod. This bell crank is secured to a shaft 77 pivotally mounted 80 in the brackets 41, such bell crank having a rearwardly extending arm provided with an opening 78 to which is connected the lower end of a spring 79, the upper end of such spring being secured to an eye bolt 80 (Fig. 90 3) fast in the upper part of the frame. Fixed upon the shafts 42 and 77, respectively, are the pawl levers 81 and 82, respectively, (Fig. 9) said levers ending in tooth members 83, 84. The lever 82 lies in a vertical plane immediately behind the plane of the lever 81, such levers cooperating with parts hereinafter to be described.

Pusher or transerrer device.

For transferring the nuts from the chamber 30 into the selector device hereinafter described, there is employed a reciprocatory pusher member illustrated in Figs. 5 and 8. The rear wall of the chamber 30 is provided with an opening which extends through the frame, such opening serving as a guide for the pusher or transerrer slide rod 85. This rod is also slideable in a guide opening in a bracket 86 depending from the lower surface of the table 4. At its forward end the rod 85 is provided with the intersecting beveled and vertical faces 87, 88, such faces serving for engagement with a nut resting upon the wear plate 31 115 and acting, upon forward movement of the rod 85, to displace such nut from the chamber 30.

A bracket member 89 is secured to the underside of the table 4 adjacent its rear edge 120 and such bracket is provided with a threaded opening for the reception of an adjustable stop screw 90, such screw being provided with a lock nut 91, if desired. The screw 90 lies in the path of movement of the bar 125 85 and serves to limit the rearward movement of the same. The lever 91 is pivoted upon a shaft 93 which extends through one of the vertical frame members and through a boss 94 projecting from such member. 130

The lever 91, at its upper end, is bifurcated to form spaced arms 95, 96, which are arranged upon opposite sides of the bar 85 and are pivotally connected thereto by means of a pin 97. The lever 91 comprises a laterally extending sleeve portion 98 from which depends an arm 99 having a roll 100 at its lower extremity. This roll is mounted on a pin or stud 101 and turns freely thereon. The roll 100 is arranged to engage within the helical slot 102 of the cylindrical cam 15, the parts being so arranged that upon rotation of said cam the lever 91 is caused to oscillate, thereby reciprocating the bar 85 in its guideways. For preventing accidental escape of a nut delivered from the chute 27 onto the plate 31, there may be provided a depending gate member as 103 (see Fig. 5), such gate member being pivoted at its upper edge, and being normally retained in vertical position by means of a light spring surrounding the pivot, or by gravity, as desired. Such gate member serves to close the open, forward side of the chamber 30, but is free to swing forwardly to permit a nut to be discharged from the chamber 30 by the positive action of the pusher rod 85.

Selector.

Cooperating with the chamber 30 and with the pusher rod 85 is a selector device indicated in Figs. 1 and 6. This selector device comprises a lever 104 mounted to swing upon the pin 51 and preferably having a hub 104^a upon which the lever 50 is mounted to swing. This lever preferably comprises a casting having a longitudinally extending channel 105 which may, if desired, be closed by a plate 106 at its forward side. This channel is of substantially rectangular cross section and of proper dimensions to permit a nut to slip down the same when in an edgewise position, but being of sufficiently restricted size to prevent tipping of the nut during its descent. The upper end of the lever 104 is preferably provided with a pair of anti-friction rollers 105, 106, respectively, such rollers being mounted upon studs 107, 108. The rollers cooperate with a longitudinal groove 109 formed in an arcuate guide member 110, such guide member being secured by means of bolts or in other desired manner to a pair of bracket arms 111, 112, respectively, which in turn are secured to the main frame by means of bolts as 113, and the bolts 26 previously referred to.

Extending laterally from the lower portion of lever 104 is a rigid arm 114, such arm being provided at its extremity with an anti-friction roller 115 carried upon a stud 116. Connected to the outer end of the bracket arm 114 is a member 117 which may be integral therewith or connected

thereto by the bolt 116, such member having an opening in which is secured the lower end of a coiled spring 118. The upper end of the spring 118 is secured to a pin 119 fixed in the guide member 110, such spring 70 tending to swing the lever 114 in a counter-clockwise direction about its axis. The roll 115 lies in the vertical plane of the cam 23 above described, such cam serving by engagement with the roll 115 to swing the lever 75 104 in a clockwise direction in opposition to the action of the spring 118.

The upper portion of the channel 105 is laterally enlarged and is divided into two divergent chambers 120, 121, respectively 80 by a centrally disposed separator member 122. This separator member, as indicated for example in Fig. 11, comprises a substantially flat rear surface 123 and curved lateral surfaces 124, 125, which intersect at the 85 edge 126. This separator member may be made integral with the lever 104, if desired, but is preferably formed of hardened material such as tempered steel and secured to the upper end of the inner wall of the 90 channel 105 by means of a screw 127 or in other desired manner. The chambers 120, 121 extend somewhat to the rear of the rear wall of channel 105 and are provided with downwardly inclined bottom surfaces 128, 95 129, respectively, (Fig. 10) which lead to the vertical portion of the channel 105. The side and front walls of the chambers 120, 121 are preferably formed by a lining member 135 which may be of hardened material 100 and furnished with guide plates such as 130, 131, respectively, where such side walls merge into the walls of channel 105. The forward portions of the outer walls of the chambers 120, 121 respectively are of curved 105 formation as indicated at 132 and 133 respectively (Fig. 11) such walls having a curvature substantially corresponding to that of the walls 124, 125, respectively, of the separator member 122. The plates 130, 110 131, where they merge into such curved walls preferably have a similar curvature.

To the left of the chamber 120 there is also provided a third chamber 134, such chamber being separated from the chamber 115 120 by the wall of the lining member 135. The chamber 134 may also be provided with a downwardly and forwardly inclined surface 136 leading to a laterally directed channel 137 which opens downwardly at the 120 point 138 at the side of the machine.

Upon the rear of the selector lever 104 there is secured a ratchet plate 139 (Fig. 9), said plate being connected to the lever by means of screws 140, and preferably being 125 of hardened material. This ratchet plate provides a ledge 141 lying in the vertical plane of the pawl 81 and a second rearwardly disposed ledge 142 lying in the plane of the pawl 82. The first-named ledge is 130

provided with ratchet teeth or notches at 143, 144, respectively, while the ledge 142 is provided with a single tooth or notch at 145. These notches are adapted for engagement by the teeth 83 and 84, respectively, as will be described more fully hereinafter. Extending downwardly from the lower end of the channel 105 is a fixed chute 146 having therein a channel forming a continuation of the channel 105. The upper end of this chute, which is fixed, may be beveled in opposite directions as indicated at 147 whereby to permit the swinging of the member 104 relatively thereto. The chute 146 may lead 10 to any desired point of discharge, as for example to the next machine employed in the finishing of the nuts. The feeding of nuts from the lower end of this chute may be controlled by a suitable gate member 15 carried by the lever 11 above referred to, if such lever be employed.

Operation.

The shaft 14 is rotated by means of a sprocket chain or other suitable device engaging the wheel 16, such wheel driving the shaft through the friction-clutch arrangement described. As the shaft is rotated, the cams 15, 22 and 23 are simultaneously 25 rotated therewith. It being assumed that nuts have been dropped promiscuously into the chute 27, the lowermost of such nuts will rest upon the plate 31. If with the parts arranged as indicated in Fig. 1 the shaft 14 is rotated in a counter-clockwise direction the cam 22 will be carried out of contact with the roller 52, thus permitting the lever member 50 to swing to the right under the action of spring 54, moving the sleeve 56 30 from out the chamber 30 by engagement of the pin 72 with the side of lever 50. As the shaft 14 continues to rotate, the cam 23 will be brought into contact with the roller 115, whereupon the selector device will be swung 35 in a clockwise direction tensioning the spring 118. Such movement of the selector lever continues until the notch 145 has been brought opposite the tooth 84 of the pawl 82 whereupon such tooth, under the action 40 of spring 79, drops into this notch, thereby locking the selector device against movement in the opposite direction. With the parts as thus positioned, the chamber 134 lies opposite the chamber 30. As the shaft 14 continues to rotate, the cam 22 comes into engagement with the roll 52, thus swinging the lever member 50 in a counter-clockwise direction. As the lever moves in this direction, the left-hand end of the sleeve 56 moves 55 into the chamber 30. If at this time a nut be resting upon the plate 31, such nut will be pushed to the left until it is brought into contact with the plate 32, such plate serving to stop further movement of the nut by 60 the action of sleeve 56. The lever 50, how-

ever, may continue to move to the left for a short distance, compressing the spring 61 between the sleeve 56 and the plate 57 secured to the lever 50. As there is normally a space between the plate 57 and the end of 70 the sleeve 56, sufficient lost motion is provided between these parts to avoid any breakage due to stopping of the sleeve 56 by engagement with a nut prior to the completion of the movement of the lever 50.

75

If the nut be eccentrically punched, or unpunched, so that its opening does not come opposite the end of the feeler bar 59, the movement of the latter to the left with sleeve 56 will be retarded (Fig. 12). Such stopping of the bar 59 will serve to swing the lever 63 in a counter-clockwise direction about its pivot 64, thus tensioning the spring 69 and carrying the contact member 67 away from the end of rod 73. As the rod 73 80 is thus unaffected by the swinging of the lever 50 to the left the pawl 82 remains in engagement with the tooth 145 of the selector lever. As the cam 22 now moves away from the roll, the lever 50 is swung to the 85 right by means of the spring 54 and substantially at the same time the groove 102 in the cam 15 acting upon the roller 100 moves the pusher rod 85 forwardly. The pusher rod engages the defective nut resting upon the 90 plate 31 and thrusts it forwardly from the chamber 30 into the chamber 134. As the nut is pushed into the chamber 134, it drops upon the inclined surface 136 and immediately slides out through the passage 137 and is discharged from the machine at the point 95 138. It will thus be seen that defective nuts are automatically discharged through the passage 137 and are not delivered to the succeeding machine.

100

If the lowermost nut which rests on plate 31 is substantially perfect, the end of the feeler bar 59 passes into the opening in the nut as the sleeve 56 moves into the chamber 30. Under such circumstances the spring 118 retains the lever 63 substantially in vertical position with the stop screw 66 engaging the plate 57. As the lever 50 completes its movement to the left the contact member 67 engages the end of the rod 73 and causes 105 it to slide to the left. As this rod moves to the left, its left-hand extremity, which engages the lug 74, swings the lever, comprising the arm 75, in a counter-clockwise direction, thus tensioning spring 79 and at the 110 same time lifting the pawl 82 whereby to release its tooth 84 from the notch 145. The spring 118 immediately swings the selector lever 104 in a counter-clockwise direction until the tooth 83 of the pawl 81 drops into the notch 144 holding the selector in such 115 position that the chamber 121 lies opposite the chamber 30. Assuming that the bottom nut N drops upon the plate 31, with the flat face 150 of the nut to the left and with 120

125

130

the chamfered face 151 thereof in position for engagement by the left-hand end of the plunger sleeve 56 (Fig. 11), the latter, upon movement to the left, will press the flat surface 150 of the nut firmly against the plate. As the diameter of the nut is, however, slightly greater than that of the cavity 32, the nut is not permitted to enter the latter, and thus fails to make operative contact with the end of the plunger 36. The tooth 83 of the pawl 81, which now engages the notch 144, thus continues to retain the selector device in such position that the chamber 120 lies opposite the chamber 30. As the driving shaft 14 revolves and the member 85 is moved forwardly, the nut positioned within the chamber 30 is thrust forwardly into the chamber 121 raising the gate 103, if such be employed, it being understood that the pusher sleeve 56 is retracted prior to the forward motion of the bar 85. As the nut passes into the chamber 120, it rests upon the inclined surface 128 and tends to slide downwardly thereon. As the nut moves downwardly, it encounters the surfaces 132 and 124, and is thus caused successively to assume the broken line positions indicated at N¹, N², Fig. 11. When the nut reaches the latter position it is free to fall vertically through the channel 105 and into the upper end of the chute 146, it being noted that as the nut passes down such channel its flat surface is presented in a forward direction. If the bottom nut in the chute drops upon the plate 31 with its chamfered side to the left,—that is to say, in a position such that it may be received within the cavity 30 with its flat surface 150 in position for engagement by the end of a sleeve 56 (Fig. 10), the movement of the latter serves to thrust the chamfered end of the nut into the cavity 34. As the end of the plunger 36 is of a diameter somewhat greater than the opening in the nut, such plunger is pushed outwardly as the nut enters the cavity 34. This movement of the plunger actuates the lever 37 and the bell crank, comprising the arm 45, and serves to tension the spring 47 and to lift the pawl tooth 83 from the notch 144. The spring 118 immediately swings the lever 104 to the left until the tooth 83 engages the notch 143. With the parts in this position the chamber 121 of the selector device is opposite the chamber 30. Upon retraction of the sleeve 56 and projection of the rod 85, the nut is pushed out from the chamber 30, raising the gate member 103, if such be employed, and passing into the chamber 121. As the nut enters the latter chamber it slides down the inclined surface 129 and in so doing encounters the surfaces 133 and 125, respectively. The nut is thus caused to assume the position indicated in broken lines N³, N⁴, Fig. 10, and from the latter position drops vertically through the channel 105.

The nut thus delivered from the chamber 120, enters the channel 105 in a position similar to that of a nut delivered from the chamber 121, and thus regardless of the position of the nut as it falls upon the plate 31, it is delivered through the chute 105 with its flat face always directed forwardly. The machine thus serves in an automatic manner not only to eject improperly formed nuts, but also to orient all perfect nuts passing down the supply chute in such manner as to cause them to occupy similar positions in the delivery chute.

It will be evident from inspection of Figs. 10, 11 that the upper end of the channel 105 is entirely open, and thus may be inspected without the necessity for removing parts or dismantling the machine. This is of especial advantage in a machine of this character as it permits the ready removal of nuts which may, for one or another reason, become jammed in the delivery channel. The machine may be operated with great rapidity and may be so co-ordinated with preceding or successive machines as to provide a continuous supply of properly positioned nuts for subsequent operations.

While the various elements of the machine have been described with reference to the specific shape and arrangement of parts herein illustrated, it is to be understood that various changes in form or arrangement, as well as in location of the various parts might well be made without departing from the spirit of the present invention.

Having thus described the invention in a preferred embodiment of the same, what I desire to secure by Letters Patent of the United States is:—

1. A nut blank sorting and positioning machine, comprising means for rejecting imperfect blanks, and means for similarly orienting properly perforated blanks.
2. A nut blank sorting and positioning mechanism comprising means for rejecting eccentrically perforated blanks and for similarly orienting properly perforated blanks.
3. A nut blank sorting and positioning machine comprising feeler means responsive to the presence of an imperforated blank, and feeler controlled means for determining the similar orientation of properly perforated blanks.
4. A machine for use in the manipulation of detached objects normally provided with perforations therethrough comprising means for rejecting defective or imperforate objects and for orienting the remaining objects whereby to bring them into like position.
5. In a machine for manipulating detached machine elements, in combination, means for supporting such elements, feeler mechanism sensitively responsive to imperfections in such elements, feeler mechanism

- responsive to the position of such elements relative to said supporting means, and independent mechanical devices controllable by the respective feeler mechanisms. 65
- 5 6. In a machine of the class described, a work support, a movable member provided with a plurality of work receiving elements and means for selectively registering said elements with said work support comprising 10 a plurality of feeler mechanisms responsive respectively to malformations in work resting upon said support and to variable positions thereof. 15
- 15 7. In combination, in a machine of the class described, a work support and a pair of work engaging feelers, such feelers being responsive respectively to variations in horizontal and vertical positions of work resting upon said support. 20
- 20 8. In combination, in a machine for manipulating nut blanks, a pair of independent feeler devices comprising plungers arranged in substantial alinement and movable toward and from one another. 25
- 25 9. In a machine of the class described, in combination, a movable selector device, resilient means for moving said device in one direction, means for moving said device in the opposite direction, a work support and a 30 pair of independent feeler devices for determining the position of such selector device relative to the work support in accordance with variations in position of work resting upon said work support. 35
- 35 10. A machine of the class described comprising a work support, a work engaging abutment, a reciprocable plunger for forcing work into engagement with said abutment, and a feeler member arranged coaxially with said plunger, such feeler member being sensitively responsive to the eccentric positioning of work relative to the work engaging surface of said plunger. 40
- 45 11. In a nut sorting machine, an abutment member having a substantially circular work engaging surface, said surface being provided with a central opening, a feeler member projecting through said opening, means for pressing work against the surface of said abutment, and feeler means associated with said work pressing means. 50
- 55 12. In a machine of the class described, an abutment member having a cavity, said abutment having an opening therein arranged coaxially of said cavity, a spring-pressed plunger seated within said opening and a locking pawl mechanism operable in accordance with movements of said plunger occasioned by the pressure of work thereagainst. 60
- 65 13. In combination in a machine of the class described, a selector lever, a work engaging abutment, a plunger constructed and arranged to press work into engagement with said abutment, a lever member for supporting said plunger, a rotatable shaft, and a pair of cams fixedly mounted upon said shaft and arranged to actuate said respective levers. 70
- 75 14. In combination, in a machine of the class described, a work support, a work positioning abutment, a hollow plunger for pressing work against said abutment, a secondary plunger slidable within said first plunger, a lever member for supporting said first plunger, a second lever member having connection with the outer extremity of said second plunger, a movable pawl, and transmission means interposed between said pawl and an element of said last-named lever. 80
- 85 15. In a machine of the class described, in combination, a stationary work support, a movable member provided with a laterally opening work receiving chamber adjacent its free extremity, reciprocable feeler means engageable with work resting upon said support and constructed and arranged to determine the registration of said chamber with said work support, and a transerrer device comprising a plunger movable in a path extending transversely of that of the feeler and constructed and arranged to push work from the work support into said chamber. 90
- 95 16. In a machine for sorting nut blanks in combination, a segmental lever having a plurality of laterally opening chambers adjacent its arcuate end, a work support having its supporting surface so constructed and arranged as to permit the selective registration of either of said chambers therewith, a plunger member movable transversely of said work support, and cam actuated means for moving said plunger at predetermined intervals whereby to transfer work from the work support to that one of such chambers which is in registry therewith. 100
- 105 17. An apparatus of the class described comprising work positioning means, a movable member having a plurality of work receiving openings therein, said member having a discharge passage, work orienting means interposed between the respective openings and said passage, and means for moving said member whereby selectively to register said openings with said work positioning means. 110
- 115 18. A sorting apparatus comprising a movable selector device having a plurality of receiving chambers, a support for objects to be sorted, feeler means movable into contact with an object resting upon said support, and means actuatable in accordance with determinations of said feeler means for positioning said selector device. 120
- 125 19. An apparatus of the class described comprising means for temporarily supporting an object, a member oscillatable about a

fixed axis and having a plurality of spaced openings adjacent its free extremity, said openings being constructed and arranged selectively to be positioned adjacent said supporting means, and means associated with said latter means for moving an object supported thereby into one of said openings.

20. In a machine of the class described a member provided with a plurality of work receiving compartments, a work support provided with an abutment having a cavity, a plunger having an axial bore, a second plunger slidable within said bore, and means controlled by the movement of said second plunger for determining the position of one of said compartments relatively to said work support.

21. A sorting apparatus comprising an oscillatable selector device having a plurality of chambers therein opening respectively into independent discharge channels, means normally operative to oscillate said device through a predetermined arc, means for supporting objects to be sorted, feeler means for determining the position of an object resting upon said support, and means for limiting the oscillation of said selector device in accordance with such determination.

22. In combination in a machine of the class described, work positioning means, a member movable relatively to said positioning means and provided with a plurality of spaced compartments, said member having a common discharge passage communicating with a plurality of said compartments and a second discharge passage communicating with another of said compartments, means capable of moving said member through a path of predetermined extent, and means for stopping said member with one or another of said compartments in registry with said positioning means.

23. In a machine of the class described, a selector device comprising a lever of substantially segmental form and provided with a plurality of spaced chambers adjacent its arcuate edge, a passage extending substantially radially through said lever and communicating with a pair of such chambers, and a second passage communicating with a third of such chambers, said second passage diverging from the first passage and opening at the edge of the lever.

24. An apparatus of the class described comprising work positioning means, a movable member having a plurality of work receiving elements, and common discharge means for receiving work from said elements, work transferring means for transferring work from said positioning means to one or the other of said receiving elements and work orienting means interposed

between the respective receiving elements 65 and said discharge means.

25. In a device of the class described, a lever member having a plurality of compartments adjacent its free extremity, a discharge passage communicating with each of 70 said compartments, and work orienting means interposed between each of said compartments and said discharge passage.

26. In a machine of the class described, in combination, a movable member having 75 a work receiving compartment, a discharge passage communicating therewith, and means interposed between said compartment and discharge passage for orienting work passing from said compartment into 80 said passage.

27. In combination in an apparatus for positioning detached objects, a work transferring device, a compartment for receiving work from said transferring device, a passage leading from said compartment, and means for orienting the work in passing from said compartment to said passage comprising a surface of curved contour.

28. In a machine of the class described, 90 an oscillatable lever member provided with a compartment adjacent its free extremity, such compartment communicating with a discharge passage extending longitudinally of said lever, a work support having an abutment, a plunger for forcing work against said abutment, said plunger being provided with an axial bore, a second plunger slidable within the said bore, means whereby to stop said lever with said compartment in registry 100 with the work support, and means controllable by said second plunger for determining the operation of said stop means.

29. In combination, in a machine of the class described, a work positioning plunger 105 having an axial bore, and a feeler element within said bore and movable relatively to said plunger.

30. In combination in a machine of the class described, a work support having an 110 abutment member, a movable selector member having a work receiving element, a pusher device for engaging work with said abutment, a transerrer member for moving work from said support into engagement 115 with the receiving element of said selector device, a drive shaft, a pair of cams upon said shaft operative to move said selector and said pusher devices in one direction respectively, resilient means for moving said 120 devices in the opposite direction, and a third cam mounted upon said shaft and having connection with said transerrer device whereby positively to move said device in opposite directions.

31. An apparatus for assorting objects comprising a support for such objects, a member provided with compartments, means

- for moving said member whereby to cause said compartments successively to register with said supporting means, feeler means movable into contact with an object carried by said supporting means, and stop means under control of said feeler means constructed and arranged to arrest the movement of said member at a predetermined point in its path of travel.
32. A sorting mechanism comprising a support for objects to be assorted, a member provided with compartments, means tending normally to move said member whereby successively to register its compartments with said supporting means, adjustable stop means for limiting the movement of said member, and automatic means for adjusting said stop means.
33. A mechanism for assorting machine elements, comprising an oscillatable of substantially segmental form, said member having a plurality of chambers adjacent its arcuate end, a movable transerrer device, spring means normally tending to swing said oscillatable member whereby successively to register said chambers with said transerrer, and means sensitively responsive to varying positions of a machine element relatively to the axis of the path of movement of said transerrer for limiting the arc of oscillation of said member.
34. A mechanism of the class described comprising a lever device of substantially segmental form, said lever device having a plurality of compartments adjacent its arcuate end, resilient means normally tending to swing said lever in one direction, a stop pawl engageable with an element of said lever for limiting the swing thereof, and automatic means for controlling the engagement of said pawl and element.
35. A mechanism of the class described comprising work positioning means and a lever member having a plurality of openings adjacent its free end, resilient means tending to swing said lever in one direction, means for swinging the lever in the opposite direction, a stop element carried by said lever and having a predetermined position relative to one of said compartments, a pawl engageable with said element, and work controlled means for determining the engagement of said pawl and element.
36. A mechanism of the class described comprising work positioning means, a lever member having a plurality of work receiving compartments, a plurality of stop elements carried by said lever and corresponding to certain of said compartments, stop pawls for engagement with said stop elements, and independent means controlled by the relation of the work to said positioning means for determining the actuation of the respective pawls.
37. A machine for manipulating detached objects comprising positioning means for such objects, a movable member having a plurality of compartments for the reception of such objects and having a discharge chute communicating with each of said compartments, a plurality of stop elements carried by said member, resilient means tending normally to move said member in one direction, a pawl engageable selectively with one or the other of said stop elements, and means for determining the position of said pawl.
38. In a machine for assorting detached machine elements, in combination a support for such elements, a segmental lever member having a plurality of compartments adjacent its free extremity, a discharge passage in said lever member communicating with a pair of adjacent compartments, a second discharge passage communicating with another of said compartments, resilient means tending normally to swing said lever member in one direction, positive means for swinging said lever member in the opposite direction, adjustable stop means for limiting the arc of movement of said lever under the action of such resilient means, and feeler mechanism associated with said work support and constructed and arranged to determine the actuation of said stop means in accordance with the position of the work relative to such work support.
39. In combination in a machine of the class described, a movable selector device, a work support having an abutment member, a feeler device associated with said abutment, pawl and ratchet mechanism for determining the position of said selector device relatively to the work support, and connections between said feeler device and an element of said pawl and ratchet mechanism whereby to determine the operation of the latter.
40. In combination in a mechanism of the class described, an oscillatable selector device provided with a plurality of ratchet teeth, a work engaging abutment, feeler mechanism associated with said abutment, a pawl member constructed and arranged for engagement with said ratchet teeth, and connections between said feeler mechanism and said pawl whereby to determine the operative engagement of the latter with said teeth.
41. In combination in a nut blank manipulating apparatus, a movable selector device comprising blank rejecting means and blank orienting means, a pair of ratchet devices carried by said selector, pawls cooperative with the respective ratchets and a pair of feeler devices connected to the respective pawls and constructed and arranged to so limit the movement of said selector as to determine the rejection or positioning of blanks

with which such feeler devices may be brought into contact.

42. In combination in a machine of the class described, a movable selector device, a bracket outstanding therefrom having a ratchet tooth therein, a locking pawl engageable with said tooth, a feeler device associated with said work support and comprising a slidable plunger, a lever member having connection with the free extremity of said plunger, and means for transmitting movement of said lever to said pawl whereby to determine the operative engagement of the latter with said ratchet tooth.
- 10 43. In a machine of the class described, a work support, a movable selector device provided with a ratchet tooth, a pawl engageable with said ratchet tooth for limiting movement of the selector device, a work feeling plunger associated with said work support, a lever having connection with the outer extremity of said plunger, and a slidable rod interposed between said lever and said pawl and constructed and arranged to be engaged by said lever during normal operation of the plunger whereby to lift said pawl out of engagement with said tooth.

44. In combination in a machine of the class described, a work support, a movable selector device provided with a ratchet tooth, a pawl, resilient means normally tending to move said pawl into engagement with said tooth, a work feeling element movable toward and from work positioned upon such support, and means interposed between said element and said pawl so constructed and arranged that, upon contact of said element with defective work, the pawl is permitted to engage such tooth and, upon movement of said feeler element into operative relationship with properly positioned and perfect work, such pawl will be lifted from said tooth.

45. In a machine of the class described comprising a segmental selector lever having work engaging elements adjacent its free extremity, and anti-friction guide means for the free extremity of said lever.

46. In combination in a machine for positioning detached machine elements, a selector lever, means for moving an element into engagement with said lever, a fixed guide rail of arcuate form, and a roller mounted upon the free extremity of said lever and engaging said guide rail.

47. In combination in a machine of the class described, a selector lever comprising a plurality of work receiving elements, an arm outstanding from said lever and provided with an anti-friction roll, a rotatable cam member engageable with said roll for swinging said lever in one direction, and spring means normally tending to swing said lever in the opposite direction.

48. A sorting apparatus comprising a movable selector device, adjustable means normally operative to move said device through a path of predetermined extent, means for stopping said selector at an intermediate point in its path, and means controlled by the work to be sorted for determining the adjustment of said stop means.

49. A sorting apparatus comprising work presenting means, work delivering means, and movable means controllable by the work as presented for sorting, and constructed and arranged similarly to orient such work and transfer it to the delivering means.

50. A sorting apparatus comprising a selector mechanism comprising a movable element, positive means for moving said element in one direction, spring means for moving said element in the opposite direction, and adjustable stop means controllable in accordance with the initial position of the work for limiting the movement of said element by said spring means.

51. A machine of the class described comprising work supporting means, a work engaging abutment, a reciprocable element for moving work into engagement with said abutment, and a feeler member associated with said reciprocable element said feeler member being sensitively responsive to the eccentric positioning of work relative to the work-engaging face of said reciprocable element.

52. In a machine of the class described, in combination, work supporting means, a movable member provided with a work receiving chamber, and reciprocable feeler means engageable with work held by said work supporting means and constructed and arranged to determine the registration of said chamber with work held by said supporting means, whereby such work may be delivered from said supporting means directly into such chamber.

53. An apparatus of the class described comprising work-positioning means, means providing a plurality of work-receiving openings, and a common discharge passage leading therefrom, work-orienting means interposed between the respective openings and said passage, and means for moving the means having the work-receiving openings therein whereby selectively to register such openings with said work-positioning means.

54. An apparatus of the class described comprising work-positioning means, a movable member provided with a plurality of work-receiving elements, common means for conducting work away from said elements, and work-orienting means interposed between the respective receiving elements and the said conducting means.

55. A mechanism of the class described comprising work-positioning means and a

member having a plurality of openings, resilient means tending to move said member in one direction, means for moving the member in the opposite direction, a stop element carried by said member, such stop element having a predetermined relation to one of said openings, a pawl engageable with

said element, and work controlling means for determining the engagement of the pawl with said element.

10

Signed by me at Boston, Massachusetts, this 14th day of July, 1921.

CHESTER T. MOREY.
